UNITED STATES PATENT OFFICE.

ROGER O. WILLIAMS, OF CARBONDALE, PENNSYLVANIA.

DESIGN FOR A CURTAIN AND SHADE BRACKET.

45,081.

Specification for Design.

Patented Dec. 23, 1913.

Application filed March 21, 1913. Serial No. 756,022. Term of patent 7 years.

To all whom it may concern:

Be it known that I, ROGER O. WILLIAMS, a citizen of the United States, residing at Carbondale, in the county of Lackawanna and State of Pennsylvania, have invented a new, original, and ornamental Design for Curtain and Shade Brackets, of which the following is a specification, reference being had to the accompanying drawing, forming part thereof.

The figure is a perspective view of a curtain and shade bracket, showing my design.

I claim:

The ornamental design for a curtain and shade bracket, as shown.

ROGER O. WILLIAMS.

Witnesses:

W. H. LLOYD,
L. E. THORPE.
